2,071,026

CONDENSER FOR AIR CONDITIONING
SYSTEMS

Powel Crosley, Jr., Cincinnati, Ohio, assignor to
The Crosley Radio Corporation, Cincinnati,
Ohio, a corporation of Ohio

Application March 12, 1934, Serial No. 715,077

9 Claims. (Cl. 257—39)

My invention relates primarily to devices for cooling and conditioning the air in a space for personal occupancy, such as a room or the like; and while it is not so restricted, it will be described in connection with a specialized form of construction such as that set forth in my copending application entitled Devices for conditioning and cooling air, Ser. No. 714,687, filed March 8, 1934. The principles of the invention will be clearly applicable in general to air conditioning systems.

The objects of my invention comprise the provision of means and a method for increasing the efficiency of such systems. More particularly my object is to do away with the necessity of disposal of moisture condensed upon the evaporator, and to employ this moisture in promoting a more rapid cooling of the refrigerant in the condenser. The increase of over-all efficiency produced in this way, becomes of great importance in connection with the conditioning of air in a small and not very well insulated space designed for immediate occupancy. However, it should be noted that the use of water condensed out of the air by the low pressure side of a refrigerating apparatus, to assist in cooling the high pressure side thereof, results in an increase in the humidity of that air which passes through the condenser; and for this reason, the use of my invention implies the provision of means whereby the air conditioned space is segregated from a space in which the condenser and associated apparatus are located.

These general and the more specific objects of my invention, which will be set forth hereinafter, or will be apparent to one skilled in the art upon reading these specifications, I accomplish by that certain construction and arrangement of parts of which I shall now describe the aforesaid exemplary embodiment.

In the drawings:

Figure 1 is an elevational view with parts in section of one form of condenser construction which I may employ.

Figure 2 is a view of an exemplary air cooling and conditioning system embodying my invention.

Figure 3 is an elevational view with parts in section of another form of condenser.

Figure 4 is a plan view of one of the condenser pans.

Figure 5 is a sectional view thereof along the lines 5—5 of Figure 4.

Figure 6 is an elevational view thereof.

Figure 7 is a sectional view of an air conditioning unit embodying my invention.

It will be understood that the particular air conditioning unit which I describe herein is one which is exemplary only of a type of unit in which my invention may be embodied, but that my invention is applicable to other types of air conditioning installations. In Figure 2 I have shown a bed indicated generally at 1 having disposed about and around it a canopy 2 upon suitable supports designed to enclose a space in which the air is to be cooled and conditioned. I have indicated broadly at 3 the cabinet of an air cooling and conditioning device. More particular description of this construction is unnecessary here but is set forth at length in my copending application hereinabove referred to. It is sufficient to point out that the air within the restricted space enclosed by the canopy 2 is cooled and conditioned essentially by being withdrawn therefrom to the cabinet 3, treated therein and returned to the canopy through suitable inlet and outlet openings provided for the purpose. The canopy 2 is of flexible material usually consisting of, or comprising, a woven fabric. Its purpose is to confine the conditioned air to the space just above the bed excepting that it may be so designed that there will be some bleeding or change of atmosphere therein. The canopy may likewise have some insulating value but it will be obvious that in a system of this character, where a small unit is employed, the utmost cooling and conditioning efficiency must be attained. A reference to Figure 7 will show in general an exemplary construction of unit for the purpose. In a cabinet 4 I have shown a partitioned off space 5 surrounded by insulating material 6. An evaporator 7 is located therein together with a fan 8 for insuring the circulation of air. The motor 9, compressor 10 and condenser 11 are located in the main part of the cabinet and outside of the insulated space 5 heretofore referred to, and there is no connection for air therebetween. The various connections between these several devices do not require special comment. It will be clear however, that there are set up in this apparatus, two separate circulations of air; one in the restricted space 7 containing the evaporator and the other in the larger part of the cabinet containing the high pressure side of the refrigerating system. This last mentioned circulation of air is set up by the fan 9a on the motor. The circulation of air in the cooling and conditioning space 7 is from and to the canopy 2, while the circulation in the larger part of the cabinet is from and to the outer air surrounding the canopy.

In a system of this character I have found that it is possible to employ the water, condensed from the conditioned air by the evaporator, in cooling the condenser by the construction which I have devised and will hereafter explain. The amount of water evaporated at the condenser will be equal to the amount condensed at the evaporator so that there is no problem of the disposal of any excess condensate. Therefore instead of delivering the condensate from the evaporator to some vessel for the purpose, I have found that when employing my construction, it is practical to deliver it to the condenser and get rid of it in this way with the advantages of added convenience and much greater efficiency.

In Figures 1 and 3 to 6 inclusive, I have shown various forms of condenser and parts thereof adapted to the practice of my invention. Essentially I have used on the tubes of my condenser, 20 pans for the holding of liquid instead of the usual flat vanes. These pans are so disposed as to fill up serially to a desired level and then spill over into the next lower pan. Moreover I have so designed these pans as to prevent the air being 25 blown over the pans from dislodging moisture therefrom so as to blow drops of moisture out into the room.

I am not restricted in the type of condenser construction which I may employ. In Figure 1 30 I have shown a condenser comprising a manifold 11a at the top thereof and a lower manifold 12. A series of vertical tubes 13 passed between these manifolds, and the pans aforesaid extend transversely of these tubes and are indicated generally 35 at 14. In Figure 3 I have illustrated another type of manifold in which a tubing 15 extends by reverse bends, in a sinuous path between an entrance fitting 16 and an exit fitting 17. The pans in this figure are indicated at 18.

40 The pans themselves are preferably shallow sheet metal stampings more particularly illustrated in Figures 4, 5, and 6. In stamping out these pans I prefer to form about the orifices through which the tubes of the condenser will 45 pass, upstanding sleeves or protrusions 18a in the metal. The edges of the pans are indicated at 19 and may advantageously have slightly projecting fins 20. Likewise I have provided an outlet orifice 21 surrounded likewise by an up- 50 standing sleeve or protrusion of the metal 22, shorter in height however than the effective depth of the pan. The pans may be made of copper or the like and when they are assembled with the tubing which constitutes the condenser, 55 they will have their outlet members 21 disposed alternately at opposite ends thereof. Thus when the topmost pan fills up, it will deliver water to the next lower pan. This water then flows toward the opposite end of the second pan until 60 this pan is filled to the overflow point whereupon it will deliver water at its opposite end to the third pan and so on. I have shown in Figures 4, 5 and 6, dents or downwardly extending protuberances 23 in the metal of the pans. The purpose of these is to form a falling off place for 65 drips of water coming through the overflow portions 21, to permit the collection of fairly large drops before these drops fall, and in this way to prevent smaller sized drops from being entrained 70 in the air passing through the condenser so as to be blown therefrom.

Figure 7 I have shown a pan 24 disposed below the evaporator 7. In this pan the moisture collecting upon the evaporator is trapped, and it is 75 carried away by a tube 25 to be delivered in the

topmost pan of the condenser 11. As hereinabove indicated, I have found that under normal conditions of operation, the condenser is capable of causing the evaporation of all of the water which condenses on the evaporator. While the 5 evaporation of water at the condenser may add somewhat to the humidity of the atmosphere surrounding the canopy, yet this is of no particular importance for the reason that it is only the space inside the canopy in which the air is to be 10 cooled and conditioned. Where my invention is applied to conditioning air in rooms or the like, it will be understood that the high pressure side of the refrigerating device will have set up in it a circulation of air to and from a space outside 15 the room.

The evaporation of condensate from the evaporator by the condenser very greatly increases the efficiency of the refrigeration device as will be evident.

Modifications may be made in my invention without departing from the spirit thereof.

It will be the usual practice in constructing my condenser to assemble the tubing and the pans as shown and then to tin or otherwise coat the entire structure with a protective metal. Where desired however, the pans may be directly brazed or soldered to the tubing. In either event, a structure is produced in which the pans are sealed in metallic contact to the tubing and not 30 only act as the ordinary cooling vanes but also serves as holding means for the fluid, the evaporation of which assists in the cooling of the condenser. The pans serve to abstract heat from the condenser and transfer it with great 35 efficiency to the liquid, and the extremely large exposed surface area of the liquid facilitates rapid evaporation and therefore efficient cooling under the influence of the air which passes 40 thereover.

Having thus described my invention what I claim as new and desire to secure by Letters Patent is:

1. A condenser for air cooling and conditioning devices comprising members providing passageways for compressed refrigerant and a plurality of cooling vanes on said members and interspaced throughout their length, said cooling vanes having the shape of shallow pans adapted to hold a fluid, the evaporation of which assists 50 in cooling the said condenser.

2. A condenser for air cooling and conditioning apparatus comprising tubing for the passage of refrigerant, a plurality of metallic vanes in contact with said tubing, said vanes being formed to contain a liquid and to present a large surface area of said liquid to air passing through said condenser.

3. A condenser for air conditioning apparatus comprising tubing forming a plurality of passageways for compressed refrigerant and a series of vanes extending transversely of said tubing, said vanes comprising shallow pans for holding a liquid, said pans having outlets, and said outlets being disposed so as to feed said liquid from 60 pan to pan at alternate ends of said condenser.

4. In a condenser for air cooling and conditioning apparatus tubing forming a passageway for refrigerant and a plurality of shallow pans extending transversely of said tubing, said shallow pans having orifices therein for the passage of said tubing, said orifices being demarcated by tubular extensions of the metal of said pans lying about and in close contact to said tubing.

5. A condenser for the purpose described com-

prising tubing and a plurality of shallow pans arranged transversely to said tubing, said pans having openings therein for the passage of said tubing, said openings having up-set portions of the metal thereabout, said tubing and said pans being joined together so as to form a tight metallic contact between said tubing and the up-set portions of said pans.

6. A condenser for the purpose described comprising tubing and a plurality of shallow pans arranged transversely to said tubing, said pans having openings therein for the passage of said tubing, said openings having up-set portions of the metal thereabout, said tubing and said pans being joined together so as to form a tight metallic contact between said tubing and the up-set portions of said pans, said pans having outlet portions characterized by openings with up-set portions of the metal thereabout, said up-set portions of the metal being less in height than the effective depth of said pans.

7. A condenser for the purpose described comprising tubing and a plurality of shallow pans arranged transversely to said tubing, said pans having openings therein for the passage of said tubing, said openings having up-set portions of the metal thereabout, said tubing and said pans being joined together so as to form a tight metallic contact between said tubing and the up-set portions of said pans, said pans having outlet portions characterized by openings with up-set

portions of the metal thereabout, said up-set portions of the metal being less in height than the effective depth of said pans, said pans being assembled so that said outlet portions occur at alternate ends of successive pans respectively. 5

8. A condenser for the purpose described comprising tubing and a plurality of shallow pans arranged transversely to said tubing, said pans having openings therein for the passage of said tubing, said openings having up-set portions of the metal thereabout, said tubing and said pans being joined together so as to form a tight metallic contact between said tubing and the up-set portions of said pans, said pans having outlet portions characterized by openings with up-set 10 portions of the metal thereabout, said up-set portions of the metal being less in height than the effective depth of said pans, and downwardly extending protuberances on said pans adjacent said outlet openings. 15

9. A condenser for the purpose described comprising tubing forming passageways for a refrigerant, a plurality of shallow pans extending transversely of said tubing, means for delivering liquid from pan to pan alternately at opposite 20 ends thereof, means for maintaining a desired depth of liquid in said pans and means for preventing the dislodgment of liquid from said pans by air passing through said condenser. 25
